UNITED STATES PATENT OFFICE.

CHARLES L. GOODRUM, OF NEW YORK, N. Y., AND EARL S. GIBSON, OF RIDGEWOOD, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed November 25, 1924, Serial No. 752,093. Renewed October 7, 1925.

This invention relates to telephone exchange systems in general and more particularly to telephone systems of the automatic type wherein selectively operable switches are employed in the controlling and completion of conversational connections.

The invention is particularly applicable to telephone systems such as shown and described in the patent to S. B. Williams, No. 1,517,331, issued Dec. 2, 1924, and in general to telephone systems wherein coordinate switches are employed for the extension of calling lines. In these systems it has been the practice heretofore to terminate subscribers' lines, as calling lines, in vertical rows of contacts of the coordinate line switches, there being a plurality of subscribers' lines appearing in a single switch. Each subscriber's line appearing in one of these switches has access to a number of horizontal link circuits which in turn are accessible to a plurality of trunks leading to successive selective stages. It has also been the practice heretofore to multiple a subscriber's line before a number of horizontal links in a particular section of the line switch, and also to multiple each of the outgoing trunks before all the links of this same section, thus a calling line would have access to an idle trunk by means of any one of a plurality of link circuits in any given section of the switch. However, should all the links in this section be busy when the subscriber initiates a call the selection of an outgoing trunk would be temporarily prevented regardless of the number of idle trunks available.

This invention has for its object, therefore, to provide an improved system for extending calling subscribers' lines by means of switches automatically responsive to the removal of a receiver at a calling station.

The foregoing object is obtained by having each subscriber's line appear before all the links in a particular section of a coordinate line switch and by having each outgoing trunk appear before but one link in this section.

A feature of the invention relates to the means for controlling the selection of a trunk which is common to a number of line switches.

A further feature of the invention resides in the means for testing available paths

through any section of a coordinate line switch, and the trunks outgoing therefrom when said trunks appear before a plurality of line switches.

A still further feature of the invention refers to the means for rendering an outgoing trunk non-available, when said trunk appears before a number of line switches.

A still further feature relates to means for rendering an idle link or an idle trunk temporarily non-available when such a link or trunk is unavailable to a calling line.

Other features and advantages of the invention not specifically mentioned will be revealed after a consideration of the following descriptions and the appended claims.

Referring to the drawing, Fig. 1 shows a plurality of subscribers' lines which terminate in contacts of the line switches such as shown in Figs. 2, 5 and 8. In the lower portion of Fig. 1 is shown a portion of the master controlling equipment normally associated with the subscribers' lines shown in Fig. 1.

Fig. 2 discloses a portion of a line switch of the coordinate type together with the remaining portion of the master switch shown in Fig. 1.

Fig. 3 in the upper portion shows the cross-point test relays which are associable with the links in the different sections of switch 200 and with the group of trunks 270. This figure also shows a number of so-called directional control relays.

Fig. 4 shows corresponding equipment to that of Fig. 1. In this instance, however, the equipment is associated with a different line switch.

Fig. 5 shows a second line switch of the coordinate type wherein a different group of calling subscribers' lines terminate.

Fig. 6 shows the cross-point relays, which are associable with the links of switch 500 and with the trunks in group 280.

Fig. 7 shows a third group of subscribers' lines terminating in the contacts of a third line switch.

Fig. 8 shows the line switch in which the third group of subscribers' lines terminate.

Fig. 9 discloses the cross-point test relays associable with the links of switch 800 and with the group of trunks 290.

Fig. 10 discloses the manner in which the

various figures of the drawing are to be arranged to give a unitary circuit disclosure.

General description.

5 The invention as described hereinafter is shown as applied to a line switch of the general type illustrated in U. S. Patent to J. N. Reynolds, No. 1,515,785, issued November 18, 1924. This type of switch consists mainly of a number of vertical rows of contacts each row being controlled by a corresponding vertically disposed operating member. Arranged for cooperation with the vertical rows of contacts, are a number of horizontal 10 link circuits, each link circuit having an operating member individual thereto. Calling subscriber's lines are terminated in contacts of certain of the vertical rows, these rows commonly being known as line verticals. 15 Outgoing trunks are terminated in contacts of other vertical rows which are known as trunk verticals. Consequently, the operation of a line vertical magnet, a trunk vertical magnet and a particular horizontal member determine the selective operation of 20 the switch in extending a calling line. For a more detailed description of the mechanical construction and operation of this kind of switch, reference may be had to the above 25 mentioned U. S. Patent to S. B. Williams.

In the drawing are shown a number of these switches namely, switches 200, 500 and 800. An inspection of the drawing will reveal the fact that each trunk is multiplied before a corresponding link in each of the switches; and furthermore, that each trunk is multiplied before one link in each section of the switches. For example, trunk 221 which is the first trunk in group 270, has an 30 appearance before the first link in section 214 of switch 200. This same trunk has an appearance before a corresponding link in a corresponding section of switch 500. The same holds true of the appearance of this 35 trunk in switch 800. Furthermore trunk 221 has an appearance before the first link in section 234 of switch 200, and before a corresponding link in each of the switches 500 and 800. A similar arrangement holds true 40 of the remaining trunks. It will be observed that each subscriber's line is multiplied to have an appearance before all the links in any one section, for example, line 110 has an appearance before all the links of section 45 214 in switch 200. Similarly, line 410 has an appearance before the group of links including link 501 in switch 500. It will be noted, therefore, that each subscriber's line is accessible to all the links of the section 50 before which it is multiplied and to all the outgoing trunks in each of the groups 270, 280 and 290. For example, line 110 is accessible to trunks 225, 226, 229, 230, etc., by means of link 217. Line 110 is also accessible 55 to trunks 223, 224, etc., by means of link 60

216. A similar arrangement obtains with regard to the remaining links in section 214, and other sections of the line switches. Should any link, for example, link 217 be busy, then all trunks appearing before this link are in reality nonselectable to a calling line terminating in switch 220. It will be observed that the trunks are divided into groups 270, 280, 290, etc. Each of these trunk groups constitutes a first, second and third choice for extending a calling line through switch 200. When a subscriber whose line terminates in switch 200, for example the subscriber at station 101, removes the receiver, line relay 103 operates, in turn causing the operation of start relay 202. Relay 202 is individual to the row of contacts as 219, wherein the calling line terminates. Relay 202 operates relay 204, which locks in series with master relay 109 and prevents a second calling line from being extended until the extension of the line 110 is completed through switch 200. Relays 109, 110, 112 and 113 form part of a master controlling circuit which is normally individual to switch 200. This master circuit times and controls the operation of switch 200 to select a trunk in group 270. The master circuit having been seized by the operation of relay 109, line vertical magnet 205 is operated as well as the directional relay 303. Relay 303 associates the group of links 214 and the trunks in group 270 with the test relays 300. Each of the test relays is double wound, the upper winding being connected to the sleeve conductor of a corresponding trunk, while the lower winding is associative by means of directional relay 303 with the group of links before which the calling line appears. The particular group 105 of horizontal links to be associated with relays 300 is determined by means of the operation of one of the relays 105, 165, etc. The test relays are designed to operate when either one or both of their windings are energized, that is, when the upper winding is connected to a busy trunk or the lower winding is connected to a busy link. 110

Should all the trunks in group 270 or all the links in the selected group be busy when the call is initiated, the selection of a trunk in the second choice group, namely, group 280 is begun. However, trunks 280 constitute the first choice for switch 500. Accordingly, with all the cross point relays 115 300 operated, a circuit is completed for relay 114, causing the master circuit of switch 500 to be associated with switch 200. This is accomplished by operating a transfer relay 412, which in turn operates directional relay 601 and releases directional relay 303. Relay 601 associates the test relays 600 with the links in section 214 and with the trunks 120 in group 280. Should there exist an idle cross point, then the proper trunk vertical 125 130

magnet and horizontal magnet in switch 200 are actuated under joint control of the master circuits of switch 200 and switch 500 which release when the idle trunk is seized.

5 Should all the cross point relays 600 be operated when directional relay 601 is actuated, indicating that either all links in section 214 or all trunks in group 280 are busy, a third transfer relay 713 is operated. Relay 713 causes the master circuit of switch 700 (which controls the group of trunks 290 as first choice) to be associated with switch 200. Relay 601 is thereupon released and relay 901 operated instead. Relay 901 associates the links of section 214 and the trunks in group 290 with test relays 900. Should there exist an idle cross point, then the corresponding relay remains normal and switch 200 is actuated to seize the idle 20 trunk in group 290. In this case the seizure of the idle trunk is under joint control of the master circuits of switches 200 and 700.

25 Should the calling subscriber's line be located in switch 500, then the selection of a trunk is made in group 280 as first choice, or in group 290 as second choice, or group 270 as third choice. Similarly, should the calling line be located in switch 800, the selection of an idle trunk is begun in group 390 as first choice, group 270 as second choice and group 280 as third choice. For example, should all trunks in the first choice of switch 800, namely, group 290 be busy, transfer relay 131 is operated and the master circuits of switches 200 and 800 operate to seize a trunk in group 270. Should all trunks in group 270 be busy, transfer relay 432 is operated and the seizure of a trunk in group 280 is placed under control of the master circuits of switches 500 and 800. Thus, it will be seen that any given group of trunks constitutes a first choice for one switch, a second choice for another switch and a third choice for still another switch.

45 While the invention has been shown as applied to three line switches and three groups of trunks, it is understood that a greater number of switches and the same number of groups of trunks may be employed. Also for the sake of preserving simplicity in the drawing there has been shown a comparatively small number of trunks in a group and each group has been shown occupying but two vertical rows of contacts. In practice, however, a far greater number of trunks occupying a correspondingly greater number of vertical rows may be employed. It will be noted that the relays of groups 300, 600 and 900, etc., are each individual to a 55 trunk even though this trunk is multiplied before a number of switches. Consequently, the number of cross point test relays is considerably less than the possible number of available cross points through the several line switches. This is accomplished by al-

lowing the test relays to be associated by means of the directional relays 301, 302, 303, 601, 602, 603, etc., with the links of any switch.

Detailed description.

When the subscriber at station 101 removes the receiver from the switchhook, with the purpose of initiating a call, line relay 103 operates by means of a circuit which includes the closed loop of the calling line and the left grounded contacts of the cut-off relay 104. Assuming that there exists an idle link, such as 217, in the section 214 of switch 200, then relay 107 is normal, and the operation of the line relay completes a circuit from ground through the left contacts of relays 107, 103 and 203, to battery through the winding of start relay 202. Assuming that the master control circuit shown in the lower portion of Figs. 1 and 2 is idle at the time the call is initiated, then relays 109, 110, 112, 113 and 132 are normal. As soon, therefore, as relay 202 has attracted its armatures, a circuit is completed from ground, through the left outer contact of relay 111, right contacts of relay 113, thence through the normal contacts of relay 109, contacts of relay 132, conductor 154, right inner contacts of relay 202 to battery through the left winding of relay 204. Relay 204 upon attracting its armatures closes a locking path which may be traced through the right winding and inner right contacts of said relay, conductor 155, winding of relay 109, to ground through the normal contacts of relay 110. Relay 109 operates in this circuit. With relay 109 actuated an energizing circuit is completed for directional relay 303. This circuit may be traced from battery, through the winding of relay 303, conductor 355, right inner armature and back contact of relay 114, left armature and front contact of relay 109 to the grounded conductor 159. Relay 303 extends this same ground through its left armature and front contact to conductor 351, winding of relay 119 to battery. Relay 119 is slow to operate and requires an appreciable interval before closing its contacts. It will be observed that the circuit above traced for operating directional relay 303 includes normal contacts of relay 114. Should there have been no available paths to the group of trunks 270 appearing in rows 210 and 211, then relay 114 would be operated in the manner to be described hereinafter and the selection of a trunk in a succeeding group would be initiated. However, for the present it may be assumed that there exists such an idle path. Thus, relay 114 is normal and the above traced operating circuit is completed for relay 303. With relay 204 operated parallel circuits are completed through the winding of line ver-

tical magnet 205, and through the right winding of relay 203, thence through the left middle contacts of relay 204, conductor 162, right armature and front contact of relay 109, to the grounded conductor 159. Should a subscriber whose line is in a different vertical group from that including line 101, have initiated a call subsequent to the actuation of line relay 103, then the vertical start relay individual to the second group and similar to relay 202 is operated, thus providing a locking circuit for relay 203. In addition, relay 203 in operating brings about the release of start relay 202, thus preventing a second calling line in the first vertical group being extended before the calling line in the succeeding vertical group has been extended.

Horizontal group relays 105 and 106 now operate in a circuit traceable from battery, through their operating windings in parallel, thence through contacts of relays 107 and 108, right contacts of relay 103, conductor 157, left outer contacts of relay 204, left normal contacts of relay 112 to the grounded conductor 159. Relay 105 locks through its right winding and locking contacts, thence through the winding of master switch relay 112 to ground as above traced. Relay 112 operates in this circuit. A locking circuit is now completed for relay 106, which may be traced from battery through the left winding and locking contacts of said relay, left outer contacts of relay 105, right contacts of relay 110, left armature and front contact of relay 112 to the grounded conductor 159. It will be noted that the above traced circuit is also extended in parallel through the winding of relay 108, which operates. With relay 112 operated a circuit is completed from battery through the winding of relay 304, conductor 152, right contacts of relay 110, left armature and front contact of relay 112, to grounded conductor 159.

It will be assumed that all the trunks having an appearance in vertical row 210 are busy, either as a result of their being connected to calling lines through contacts of switch 200, or through switch 500, or through switch 800. For example, trunk 221 may be connected to line 410 by means of a link, as 501 in switch 500, thus rendering trunk 221 non-selectable at switch 200. Similarly, the remaining trunks which appear in vertical row 210 of switch 200 and in corresponding vertical rows 510 and 810 of other line switches are assumed to be non-selectable. It will be further assumed that trunk 226 which appears in vertical rows 211, 511 and 811 of the several line switches is the first idle trunk in the first group of trunks 270. It will also be assumed that horizontal link 215 is busy, while horizontal links 216 and 217 are idle.

An inspection of Figs. 2 and 3 will render clear the relation of the various cross point test relays to the corresponding trunks. For example, relay 321 is individual to trunk 221 and is in an operated condition when this trunk is non-selectable. Relay 323 is individual to trunk 223, relay 325 to trunk 225 and similarly for the remaining relays. While but two sections of switch 200 are shown and but six trunks terminating therein, it will be understood that there may be a greater number of sections and a greater number of trunks, dependent on traffic conditions. Since trunks 221, 223, 225, etc., in vertical row 210 are busy, then the corresponding cross point relays 321, 323, 325, etc., are operated. Accordingly, the operating circuit for trunk vertical magnet 231 is broken at the upper inner armatures and back contacts of these relays. Since, however, trunk 226 is assumed to be idle, relay 326 individual thereto is normal, and a circuit may be treated from battery, through the winding of trunk vertical magnet 218, conductor 251, contacts of relay 303, conductor 357, upper inner armature and back contact of relay 326, upper inner armatures and front contacts of relays 324, 322, 325, etc., in series, conductor 353, left inner contacts of relay 204, conductor 156, contacts of relay 119, to ground through the right armature and front contact of relay 109. With magnets 205 and 218 operated, the release of the master switch is initiated, under the control of the timing relays 110 and 113, which are designed to be slow in operating. The period elapsing between the initial energization of relay 110 and the complete operation of relay 113 is sufficient to permit a test to be made of the horizontal links in section 214 of switch 200 and to permit the operation of a horizontal magnet corresponding to an idle link in this section. Accordingly, relay 110 is energized by means of a circuit which may be traced from battery through its winding, conductor 158, lower inner armatures and front contacts of magnets 205 and 218 to ground. After an interval when relay 110 has completely attracted its armatures, it closes an obvious energizing circuit for relay 113, which also attracts its armatures after an interval has elapsed.

Since the calling line is accessible to a plurality of links in section 214, including links 215, 216, 217, etc., and since the idle trunk 226 has an appearance before link 217 alone in this section and furthermore, since link 216 has been assumed idle, while link 215 has been assumed busy, it becomes necessary to render link 216 momentarily non-selectable. This is accomplished by the operation of the start wire advance relay 116, which is individual to link 216. Since link 215 has been assumed busy, relay 115

is energized in series with the horizontal magnet 235, as described hereinafter in detail, whereas relay 116 is now energized in a circuit which may be traced from battery, 5 through both windings of magnet 236, left winding of relay 116, contacts of relay 106, conductor 161, contacts of relay 303, lowermost armatures and front contacts of relays 324 and 323, conductor 361, right outer contacts of relay 114, to the grounded conductor 159. Should there be other idle intervening links between link 216 and link 217 the relays similar to relay 116 are energized in circuits corresponding to that already 10 traced for relay 116. It is to be noted that the resistance of the left windings of relays 115, 116, etc., is sufficiently high to prevent the operation of the corresponding horizontal magnets 225, 226, etc. Relays 115 and 116 15 lock through their right windings and locking contacts thence through the left inner contacts of relays 105 and 108, right contacts of relay 103, conductor 157, left outer contacts of relay 204, lower outer armatures 20 and front contacts of magnets 205 and 218 to ground. Since trunk 226 is idle, relay 117 remains normal when magnet 218 is energized, whereupon a circuit is completed 25 from battery through the right winding of magnet 237, right armature and back contacts of relay 117, right armatures and front contacts of preceding relays 116, 115, etc., to ground, as above traced. Magnet 227 completes a locking circuit traceable from battery through both windings in series with 30 the left winding of relay 117, thence through contacts in row 219, test conductor of link 217, contacts in row 211, sleeve conductor of trunk 226, upper outer armature and back 35 contact of relay 326, lower outer contacts of relay 304, upper inner armature and front contacts of relays 324, 322, 325, etc., in series to ground over conductor 353, as hereinbefore traced. Relay 117 does not operate 40 at this time, however, since it is shunted by the original energizing circuit traced for magnet 237. The calling line 110 is now extended by means of link 217 to the idle trunk 223, whereupon the sleeve conductor of this 45 trunk is maintained grounded at a succeeding selective switch, as described in detail in the above mentioned patent to S. B. Williams.

At the end of the interval determined by 50 the operation of relay 113, when this relay has completely attracted its armature, the holding circuit for relay 204 and master relay 109 is broken, these relays thereupon release. The holding circuit of horizontal group relay 105 and master relay 112 is also broken at this time. The release of relay 204 opens the energizing circuits of relay 203 and the line vertical magnet 205. Magnet 205 thereupon restores to normal. Relay 55 109 in releasing opens the energizing circuit of the directional control relay 303, which in turn causes the release of trunk vertical magnet 218. With relay 105 normal the shunt is removed from around the winding of relay 117 and this relay energizes in series with the windings of magnet 237, as hereinbefore traced. Since link 216 was assumed to be idle at the initiation of the operation, the locking circuit through the right winding of this relay is broken by the release of the master switch, thus releasing relay 116 and restoring link 216 to its selectable condition. It will be noted, however, that link 215 which was assumed busy when the master switch was seized, is still 70 maintained busy by the continued energization of the horizontal magnet 235 in series with the left winding of relay 115 to the grounded sleeve test conductor of the busy link 215. With the master switch restored 75 to normal, relay 304 releases, whereupon the shunt is removed from around the upper winding of relay 326 and this relay now operates in a circuit which may be traced from battery, through the upper winding thereof, 80 to the grounded sleeve conductor of trunk 226. 85

As soon as the connection is established through switch 200, cut-off relay 104 operates and releases the line relay 103. The 90 connection is now in a stable condition and the master switch associated with frame 200 is rendered available in controlling other connections. 95

All paths busy in first group.

It will next be assumed that both trunks 225 and 226, which are the last trunks appearing in rows 210 and 211, respectively, are alone idle, when the master switch is seized, 100 but that link 217 giving access to these trunks is busy while preceding links, as 216, etc., are idle. The sequence of operations under these conditions is similar to that already described, as far as the point where 105 the cross-point test is made. In this case, since link 217 is not selectable, line 110 cannot be extended to either of the trunks 225 and 226, even though these trunks are idle 110 at the time. Accordingly, with relays 303 and 106 operated, as hereinbefore described, 115 a circuit is completed from battery, through the lower windings of relays 325 and 326 in parallel, contacts of relay 303, conductor 650, right inner contacts of relay 106, thence 120 to the grounded sleeve conductor of link 217. Since link 217 is the only link in section 214 that gives the calling line access to the idle trunks 225 and 226 and since both these trunks have been thus rendered non-selectable 125 by the operation of relays 325 and 326, line 110 cannot be extended to any trunk in the first group with which the master switch shown in Fig. 1 is associative. It will be seen, therefore, that all the cross-point test 130

relays associated with the first group of trunks are operated either as a result of the corresponding trunks being busy or as a result of the available links being busy. 5 Therefore, it is necessary to perform a test of the trunks in group 280. However, since the selection of a trunk in group 280 is controlled by the master circuit of switch 500, this master circuit must be associated 10 temporarily with switch 200. Accordingly with all the cross-point test relays of the first group operated, as above described, a circuit is completed from battery through the right winding of relay 114, conductor 15 656, lower inner armatures and front contacts of relays 326, 324, etc., in series, to ground. Relay 114 is associated with switch 200 and is individual to the first group of trunks 270 which includes trunks 221, 222, 20 223, etc. A locking circuit is completed for relay 114 which may be traced from battery through the left winding and locking contact thereof, thence to the grounded conductor 159. Assuming that there exists an idle 25 trunk in group 280, then relay 414 which is individual thereto is normal, and it becomes necessary to associate the master switch shown in Fig. 4 with switch 200. The association of this second master switch is 30 initiated by the operation of transfer relay 412. This relay operates in a circuit traceable from battery through its winding, left contacts of relay 426, left armature and back contacts of relay 414, conductor 451, right 35 inner armature and front contact of relay 114, left armature and front contact of relay 109, to grounded conductor 159. Assuming the master switch shown in Fig. 4 to be idle when relay 412 operates, a circuit is now 40 closed through the right winding of relay 425, left outer armature and front contact of relay 412, right outer armatures and back contacts of relays 502, 503, etc., in series, contacts of relay 433, right armature and back 45 contact of relay 409, left normal contacts of relay 410, conductor 452, to ground at the armature of relay 111. Relay 425 operates and thereupon closes a locking circuit through its left winding and locking contact, winding of relay 433, to ground through the left contacts of relays 410 and 111. Relay 433 operates in this circuit and renders the master switch associated with switch 400 busy. The preceding circuits 50 were completed under the assumption that no subscriber, whose line terminates in switch 400, had initiated a call at the instant that the master switch was seized by the operation of relay 412. Should such a subscriber have initiated a call immediately prior to the operation of the relay 432, a corresponding start relay 502, or 503, would be operated, thus preventing relay 425 from operating and seizing this master switch. 55 The calling subscriber, whose line terminates

in switch 200, must, therefore, await the release of the master switch which is individual to switch 400.

When relay 425 operates an energizing circuit is closed for relay 426 which may be traced from battery through the left winding thereof, right outer contacts of relay 425, left outer armature and back contact of relay 414, conductor 451, right inner armature and front contact of relay 114, to ground through the left armature and front contact of relay 109. Relay 426 locks through its right winding and locking contact provided another relay similar to relay 412 is energized. Relay 425 also closed an operating circuit for directional relay 601. This circuit may be traced from battery through the winding thereof, conductor 652, right outer contacts of relay 425, left armature and back contact of relay 414, to the grounded conductor 451. Relay 601 extends this same ground through its left contacts to conductor 656, thence to battery through the winding of slow operating relay 419.

The relation of the cross-point relays 627, 628, 629, etc., to the group of trunks 280 is similar to that already described in connection with relays 321, 322, etc., and the trunks in group 270. The drawing shows trunk 227 as having an appearance before the first link in section 214, while trunk 229 is shown as appearing before the last link in this same section, it being understood that other trunks will have an appearance in row 212, each before a different link in section 214. A similar arrangement holds true for the trunks appearing in vertical row 213. It will be assumed that link 217 is the only idle link in section 214, and that trunks 227, 228 and 230 are the only idle trunks in group 280. Since, however, link 215 which gives access to the idle trunks 227 and 228 is busy, it becomes necessary to render these trunks momentarily non-selectable while a test is being made of the available cross points in switch 200.

Since link 215 is busy, a circuit may be traced from battery through the lower windings of relays 627 and 628 in parallel, contacts of relay 601, conductor 651, conductor 152, right outermost contacts of relay 106, to the grounded test conductor of link 215. The operation of relays 627 and 628 renders trunks 227 and 228 momentarily non-selectable. Since it has been assumed that all remaining links in section 214 are idle, it is necessary to render all these links temporarily non-selectable with the exception, however, of link 217 before which the idle trunk 230 appears. Accordingly, relay 116 is operated by means of a circuit completed from battery through the windings of magnet 236, left winding of relay 116, right contacts of relay 106, conductor 161, contacts of relay 601, lowermost armature and front

contacts of relays 632 and 631, conductor 653, right outer contacts of relay 414 to ground through the left contacts of relay 410. Similar circuits may be traced for succeeding relays corresponding to 116 and associated with remaining idle links in section 214. The corresponding circuit for operating relay 117, however, is broken at the lowermost contacts of relay 630, which 10 relay is normal at this time. When relay 419 has closed its contacts a circuit for trunk vertical magnet 232 may now be traced from battery through the winding thereof, conductor 359, contacts of relay 601, upper innermost armature and back contact of relay 630, upper inner armatures and front contacts of relay 632 and 628, in series, conductor 654, right middle contacts of relay 425, contacts of relay 419, armature and front 15 contact of relay 433, left normal contacts of relay 409, to ground through contacts of relays 410 and 411. With magnets 205 and 232 operated the release relay 110 is energized in the manner hereinbefore described, to 20 bring about the release of the master switch associated with the frame 200. At this time also a parallel operating circuit is completed through the winding of the release relay 410. This circuit may be traced from 25 battery through the winding of relay 410, right inner contact of relay 425, conductor 455, thence to the grounded conductor 158. Relay 410 after an interval causes relay 413 to operate, whereupon ground is removed 30 from the windings of relays 425 and 433 and these relays release. Relay 425 causes release of directional relay 601. The master switch of Fig. 4 is thus released for controlling other connections. The connection 35 through the switch 200 is maintained by magnet 237 which is locked in series with the left winding of relay 117, contacts of switch 200 to the grounded sleeve conductor of trunk 230. It will be noted that release of 40 directional relay 601 opens the previously traced operating circuits for the relays 116, etc., associated with the idle links in switch 200. When the group relay 106 releases the locking circuit of these relays is broken and 45 the same release to render the associated links selectable.

All paths busy in first and second groups.

It will next be assumed that a test has been 55 made of the trunks in group 280 and that all available paths to these trunks are busy. It will be also assumed that trunk 228 alone in this group is idle while link 216 alone in section 214 is idle. Under these conditions it will be noted that because of the 60 busy condition of link 215, trunk 228 cannot be selected regardless of its being idle. The operations in this case are similar to those already described in connection with 65 the selection of a trunk in group 280, relay

412 operating as already described to associate the master circuit of switch 500 with switch 200. In this case, however, when the cross-point test is to be made and since trunk 228 alone is assumed to be idle, then all of 70 the cross-point relays shown in Figs. 3 and 6 are operated with the exception of relay 628 which is individual to the cross-point determined by trunk 228 and link 215. Accordingly, when directional relay 601 operates as above described, a circuit is closed from battery through the lower winding of relay 628, contacts of relay 601, conductors 651 and 152, right outer contacts of relay 106 to the grounded test conductor of link 215. 75 All the cross-point relays having thus been operated as an indication that no available paths exist to group 280, relay 414 is operated by means of a circuit which may be traced from battery through the right winding 80 thereof, conductor 655, lower inner armatures and front contacts of relay 630, 632, etc., in series to ground. Relay 414 immediately locks through its left winding and locking contact, to ground through the left 85 armatures of relays 410 and 111. Relay 414 at its left armature and back contact opens the previously described energizing circuit of relay 601 which thereupon releases in turn causing the release of relay 628. All the remaining cross-point relays shown in Figs. 3 and 6 being maintained energized by means of the grounded sleeve conductors of the associated busy trunks.

The master switch shown in Fig. 7 which 100 is individual to switch 800 is next associated with the third group of trunks 290. Assuming that an idle trunk exists in this group, relay 714 is normal, and transfer relay 713 operates, by means of a circuit completed 105 from battery through the winding thereof, left contacts of relay 726, middle armature and back contact of relay 714, conductor 751, left outer armature and front contact of relay 414, conductor 451, thence to ground 110 through the right inner armature and front contact of relay 114. In a manner similar to that described in connection with relay 425, an operating circuit is completed for relay 725, and assuming the master switch 115 shown in Fig. 7 to be idle then this latter relay locks by means of a circuit completed through its left winding and locking contact in series with the winding of relay 715. Relay 715 operates in this circuit and renders the associated master switch busy. Directional relay 901 is now operated in a circuit traceable from battery through the winding of said relay, conductor 952, right outer contacts of relay 725, left middle armature and back contact of relay 714, to ground over conductor 751 as above traced. Relay 901 in turn causes energization of slow operating relay 719. With relay 901 operated 120 the cross-point test relays 900 are associated 125

with the group of trunks 290 and with the links in section 214. In a manner similar to that already described in connection with the cross-point relays of groups 300 and 600, 5 an idle path is determined in section 214 which gives access to a trunk in group 290 and the proper horizontal magnet corresponding to this idle path is actuated. As soon as a trunk vertical magnet, for example 10 magnet 233, is operated ground is extended as hereinbefore described over conductor 158, to operate relay 110, and over conductor 455 to operate relay 410. This same ground is extended by means of conductor 755 and the right inner contacts of 15 relay 425 to the winding of release relay 710. In a manner deemed to be already familiar, relays 110, 410 and 710 bring about the release of the associated master switches 20 and also the release of magnets 205 and 233.

In the foregoing detailed description, it has been assumed that the calling subscriber's line terminates in contacts of switch 200 with which the master switch shown in the 25 lower portions of Figs. 1 and 2 is normally associated. Should, however, the calling line be located in a different line switch, as for example, switch 500 the selection of an idle trunk in group 280 will take place since the 30 master circuit of switch 500 is normally associative with this group of trunks. Should all available paths in this group be busy when the subscriber at station 401 initiates a call, then relay 414 operates. The circuit 35 for operating relay 414 may be traced from battery, through the right winding thereof, conductor 655, thence through the lower inner contacts of all the busy cross-point relays 600 to ground. Relay 414 locks and 40 brings about the release of directional relay 602, which it will be noted is operated in a circuit similar to that hereinbefore described in connection with relay 301. Assuming there to be an idle trunk in group 45 290, then relay 714 is normal, and a circuit is closed for transfer relay 723. This circuit may be traced from battery, through the winding of relay 723, left contacts of relay 724, left outer armature and back contact 50 of relay 714, conductor 752, right inner armature and front contact of relay 414, left armature and front contact of relay 409 to ground through the left contacts of 55 relays 410 and 111. In a manner deemed to be already familiar, the operation of transfer relay 723 brings about the actuation of directional relay 902 and the subsequent association of the master switch of Figs. 7 and 8 with switch 500 whereby an idle 60 trunk in group 290 is selected. Should, however, all paths to trunks in groups 280 and 290 be simultaneously busy, then relays 414 and 714 are operated. Relay 714 locks and causes the release of directional relay 65 902. A circuit is also completed for trans-

fer relay 121 which may be traced from battery, through the winding thereof, left contacts of relay 123, left middle armature and back contact of relay 114, conductor 756, left outer armature and front contact of relay 714, conductor 752, right inner armature and front contact of relay 414 to ground. Relay 121 causes the successive actuation of relays 122, 123 and directional relay 302. Relay 302 associates the cross-point relays 75 300 with the horizontal links of switch 500 for the purpose of selecting an idle path in switch 500 as hereinbefore described.

Similarly, should the calling line terminate in switch 800 then upon the removal of the receiver by the calling subscriber start relay 803 operates in turn causing the operation of relay 804 which locks in series with relay 709. A line vertical magnet as 805 and directional relay 903 thereupon operate 85 and the cross-point relays 900 are associated with the links in switch 800 and with the group of trunks 290. Should there be an idle trunk in this group, and an available link giving access thereto, then the corresponding horizontal magnet is operated to complete the extension of the calling line. The release of the master switch as brought about by the actuation of relay 710 subsequent to the operation of a trunk vertical 90 magnet as is already described. The release of the master switch in turn causes the release of the line vertical magnet 805 and the operated trunk vertical magnet. Should all the cross-point relays 900 be energized 95 as a result of the corresponding links in switch 800 being busy or as a result of the group of trunks 290 being busy when relay 903 operates, then relay 714 is energized 100 through its right winding, thus opening the circuit of directional relay 903 which releases. Should one of the relays 300 be released indicating an idle trunk in group 270, then relay 114 is normal and transfer relay 131 operates. Relay 131 brings about 105 the actuation of directional relay 301 and the association of cross-point relays 300 with the links of switch 800 and the trunks in group 270. Should all the relays 300 be operated, indicating an all-trunks busy condition in group 270, then relay 114 operates in turn releasing relay 301. With relays 114 and 714 operated, a circuit is closed for transfer relay 432 which associates the master switch of Figs. 4 and 5 with the switch 110 800. Subsequently, a trunk and horizontal magnet of switch 800 are operated should there be an available path to an idle trunk in group 280, and this idle trunk is seized 115 as already described in detail.

What is claimed is:

1. In combination, subscribers' lines arranged in groups, an automatic switch for extending said lines comprising groups of link circuits corresponding to said groups of 120 130

- lines, outgoing trunks each accessible to but one link in each of said groups of links, testing devices for said trunks and each associative with a link in any of said groups of link circuits, and means dependent upon the condition of said testing devices for causing said switch to operate to seize a trunk. 5
2. In combination, subscribers' lines arranged in groups, an automatic switch responsive to the initiation of a call on any of said lines for extending the same, groups of link circuits in said automatic switch corresponding to said groups of lines, a plurality of outgoing trunks, each trunk accessible to but one link in each of said groups of links, testing devices for said trunks and each associative with a link in any of said groups of link circuits, and means for actuating said switch to seize one of said trunks 10 dependent upon the condition of the associated testing devices. 15
3. In combination, subscribers' lines arranged in groups, an automatic switch responsive to the initiation of a call on any of said lines for extending the same, groups of link circuits in said automatic switch corresponding to said groups of lines, a plurality of outgoing trunks each trunk accessible to but one link in each of said groups of links, testing relays for said trunks and each associative with a link in any of said groups of link circuits, and means for actuating said switch to seize one of said trunks 20 dependent upon the condition of the associated testing relay. 25
4. In combination, subscribers' lines arranged in groups, an automatic switch for extending said lines and comprising groups of link circuits corresponding to said groups of lines, outgoing trunks, each trunk accessible to one link in each of said groups of links, a plurality of testing devices, each associative with a trunk and associative with a link in any of said groups, means dependent upon the condition of said devices for operating said switch to connect a link 30 to a line and to an idle outgoing trunk. 35
5. In combination, subscribers' lines arranged in groups, an automatic switch for extending said lines comprising groups of link circuits corresponding to said groups of lines, outgoing trunks, each trunk forming a cross point with one link in each of said groups of links, testing devices each individual to a trunk and associative with the corresponding link in each of said groups of links, means dependent upon the condition of said devices for operating said switch to connect a line and to a trunk, and means responsive to said connection for rendering all cross points involving said link non-selectable. 40
6. In combination, subscribers' lines arranged in groups, an automatic switch for extending said lines comprising groups of link circuits corresponding to said groups of lines, each trunk having an appearance before one link in each group of links, each appearance forming a cross point for completing connections, testing devices each individual to a trunk and associative with a plurality of said cross points, and means dependent upon the condition of said testing devices for causing said switch to operate to extend a calling line through an idle one of said cross points. 45
7. In combination, subscribers' lines arranged in groups, automatic switches for extending said lines, said switches comprising groups of link circuits corresponding to said groups of lines, a plurality of trunks common to all of said switches, each trunk having an appearance before one link in each group of links in all of said switches, testing devices accessible in common to all of said switches and each individual to one of said trunks, means responsive to the busy condition of a trunk for operating the device individual thereto to render said trunk non-selectable at all of said switches, and means dependent upon the condition of said devices for operating one of said switches to seize an idle one of said trunks. 50
8. In combination, subscribers' lines arranged in groups, automatic switches for extending said lines each switch comprising groups of link circuits corresponding to said groups of lines, a plurality of trunks common to all of said switches, each trunk having an appearance before one link in each group of links of all of said switches, a plurality of testing devices each individual to a trunk and associative with a link in any of said switches, and means dependent upon the condition of the trunks and the links with which said devices are associated for operating one of said switches to seize an idle one of said trunks. 55
9. In combination, subscribers' lines arranged in groups, automatic switches for extending said lines, each switch comprising groups of link circuits corresponding to said groups of lines, a plurality of trunks common to all of said switches, each trunk having an appearance before one link in each group of links of all of said switches, a plurality of testing devices each individual to a trunk and associative with a link in any of said switches, and means responsive to the initiation of a call and dependent upon the condition of the trunks and the links with which said devices are associated for operating one of said switches to seize an idle one of said trunks. 60
10. In combination, subscribers' lines arranged in groups, automatic switches for extending said lines, each switch comprising groups of link circuits corresponding to said groups of lines, a plurality of groups of trunks each trunk having an appearance in 65

all of said switches, testing devices each individual to a trunk, means for associating certain of said devices with a particular group of links in any one of said switches, 5 and means dependent upon the condition of said group of links and the corresponding group of trunks for associating in succession other of said test devices with said group of links, for the purpose of extending a line 10 to a trunk in another group of trunks.

11. In combination, subscribers' lines arranged in groups, automatic switches for extending said lines each switch comprising groups of link circuits corresponding to said 15 groups of lines, groups of trunks each trunk appearing in all of said switches, said groups constituting a plurality of successive choices for extending one of said lines, testing devices arranged in groups corresponding to 20 said groups of trunks, each device individual to a trunk, means for associating a first group of devices with any group of link circuits, means dependent upon the condition of said group of link circuits for successively associating other groups of devices 25 with said group of link circuits, and means dependent upon the condition of any group of devices for operating one of said switches to extend a line by means of a link in said 30 group of links to an idle one of said trunks.

12. In combination, subscribers' lines arranged in groups, automatic switches for extending said lines comprising groups of link circuits corresponding to said groups of 35 lines, groups of trunks constituting successive groups of choices for extending said lines, testing devices each individual to a trunk, means for associating a portion of said devices with a particular group of links 40 in one of said switches, means dependent upon the busy condition of said links in said group and the condition of the first choice

trunks for associating other portions of said devices in succession with said group of links to seize a trunk in a succeeding choice 45 group.

13. In combination, subscribers' lines arranged in groups, automatic switches for extending said lines comprising groups of link circuits corresponding to said groups of lines, a plurality of trunks, each trunk adapted to form a junction with one link in each group of links, testing devices less in number than the number of said junctions, means for associating said devices in succession 55 with different groups of junctions for the purpose of making a test thereof, and means dependent upon the finding of an idle junction for operating said switch to seize said junction to extend a calling line there- 60

14. In combination, subscribers' lines arranged in groups, an automatic switch in which said lines terminate and comprising groups of link circuits, groups of trunks appearing in contacts of said switch, said trunks and links forming groups of junctions for extending calling lines, testing devices arranged in groups corresponding to said groups of trunks each device individual to a trunk, means for associating a group of devices with a first group of junctions, means dependent upon a busy condition of said first group of junctions for associating in succession other groups of testing devices with remaining groups of junctions, and means effective upon the finding of an idle junction in any group for operating said switch to extend a calling line therethrough. 75

In witness whereof, we hereunto subscribe 80 our names this 24th day of November A. D., 1924.

CHARLES L. GOODRUM.
EARL S. GIBSON.
